UNITED STATES PATENT OFFICE

99,525

DESIGN FOR A PAPER FILE

Helen L. Schridde, Philadelphia, Pa.

Application February 13, 1936, Serial No. 61,127

Term of patent 14 years

To all whom it may concern:

Be it known that I, Helen L. Schridde, a citizen of the United States, and a resident of Philadelphia, county of Philadelphia, State of Pennsylvania, have invented a new, original, and ornamental Design for a Paper File, of which the following is a specification, reference being had to the accompanying drawing forming a part thereof, wherein:

In the said drawing, the base of the paper file shown therein is of circular outline.

I claim:

The ornamental design for a paper file as shown and described.

HELEN L. SCHRIDDE.
